UNITED STATES PATENT OFFICE

FRANK R. BELLUCHE, OF RACINE, WISCONSIN

BRONZING MACHINE

Application filed July 27, 1928. Serial No. 295,718.

This invention relates to means for increasing the efficiency of exhausters used in connection with bronzing machines.

In bronzing machines it is customary to provide an exhauster for drawing off excess bronzing material and while this method functions satisfactorily, it has been found that much of the material becomes lodged on the bottom of the machine where it remains, and therefore, it is an object of this invention to provide means for more efficiently removing excess bronzing material from the interior of the machine.

Another object of this invention resides in the provision of a bronzing machine equipped with an exhauster cooperating with a cyclone or separator receptacle and having means whereby the discharge of the cyclone or receptacle is utilized to increase the efficiency of the exhauster.

And a more specific object of this invention resides in the provision of means for connecting the interior of a bronzing machine with the air outlet of a cyclone or separating receptacle whereby both suction and pneumatic pressure are employed to thoroughly remove all of the excess material from the interior of the machine.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

The single view is an end view of a bronzing machine embodying my invention with parts thereof broken away and in section.

Referring now more particularly to the accompanying drawing, in which like numerals designate like parts throughout the

several views, 5 and 6 designate the side frames of a bronzing machine of that type more at length described in my copending application, Serial No. 285,030 filed June 13, 1928. The side frames are maintained in proper spaced relation by any suitable means including cross bars and the like, not shown, and rotatably mounted therebetween are the various work carrying cylinders, of which the bronzing cylinder 7 and a plurality of 55 cleaning rolls 8 are only shown.

Inasmuch as the particular construction of the bronzing machine and the manner in which the work is fed through the machine has no part in this invention, the same is not shown nor described, suffice it to say that the cleaning rolls 8 remove the excess bronze from the sheets or work as they are carried past them by the bronzing cylinder 7, the excess bronzing material falling downwardly to the 60 bottom 9 of the machine.

The side frames 5 and 6 are provided with similar openings 10 and 11 in line with the bottom 9, the opening 10 communicating with an exhauster 12 through a passage 13 formed 75 by a box-like structure 14 secured to the side frame 5 by screws or the like 15. The exhauster 12 is mounted in any suitable manner and is driven by a drive belt, not shown, trained about a pulley 16.

Connected with the outlet of the exhauster is a duct or tube 17 which extends upwardly to have its discharge end 18 communicate with the upper portion of a cyclone or separator 19 of conventional construction. A bracket 20 secured to the side frame 5 suitably supports the cyclone and a second bracket 21 likewise secured to the side frame carries an adjustable supporting means 22 at its outer end to maintain a container 23 directly beneath the lower end of the cyclone 19. As is well known, the cyclone 19 functions to separate the air and bronzing material discharged into it by the exhauster.

An air outlet 24 is formed at the upper portion of the cyclone and is provided with two ducts 25 and 26 equipped with a damper 27 arranged to regulate the draft through the duct 26. The duct 25 opens to the atmos- 95 100

phere and the duct 26 has its opposite end connected with the opening 11 in the side frame 6 to communicate with the interior of the bronzing machine. As will be readily apparent, a pressure current of air is forced into the interior of the bronzing machine which assists the suction of the exhauster to thoroughly remove the excess bronzing material in the machine, the damper 27 being adjustable to regulate the proportion of air passing through the duct 26 to that being discharged through the outlet 25.

If desired, a false bottom 28 may be provided consisting of a plurality of angularly disposed, spaced cross bars 29 arranged to direct the pressure current of air upwardly and toward the outlet 10. The excess material drops onto the false bottom from where it is more easily picked up by the air currents to be conveyed to the cyclone.

From the foregoing description, taken in connection with the accompanying drawing, it will be readily apparent to those skilled in the art to which an invention of this character appertains, that I provide means for more efficiently removing excess bronzing material from the interior of a bronzing machine which utilizes the normal air discharge of the cyclone or separator.

What I claim as my invention is:

1. In a machine for applying powdered material to work passed through the machine, the excess of material being removed from the work, a plurality of spaced elements upon which the excess material drops, means for producing a vacuum to draw the excess material from the machine, means for conducting a pressure current of air over and under the spaced elements, and said spaced elements being inclined to bias the pressure current of air upwardly to assist the vacuum means in drawing the excess material from the machine.

2. In a machine for applying powdered material to work passed through the machine, the excess of material being removed from the work, a plurality of spaced slats upon which the excess material falls, means for producing a vacuum to draw the excess material from the machine, means for conducting a pressure current of air over and beneath the plurality of spaced slats, and said slats being inclined at an upward angle to bias the pressure current of air passing over and beneath them upwardly to assist the vacuum means in removing excess material from the machine.

3. A device to collect bronzing dust comprising a chamber in which the dust is collected, having an opening in the lower portion thereof, a draft creating means producing a stream of air, and having an intake thereof connected with said opening for withdrawing dust from said chamber, a dust separator connected with said means for re-

ceiving dust and separating it from the stream of air, means for returning the air stream from the separator to the lower portion of said chamber, and means in the lower portion of said chamber for agitating the returned air to assist in the removal of the dust.

4. A device to collect bronzing dust comprising a chamber in which the dust is collected having an opening in the lower portion thereof, a draft creating means producing a stream of air, and having the intake thereof connected with said opening for withdrawing dust from said chamber, a dust separator connected with said means for receiving the dust and separating it from the stream of air, means for returning the air stream from the separator to the lower portion of said chamber, means in the lower portion of said chamber for agitating the returned air to assist in the removal of the dust, and means to regulate the force of said returned air.

5. A device to collect bronzing dust comprising a chamber in which the dust is collected having an opening in the lower portion thereof, a draft creating means producing a stream of air, and having the intake thereof connected with said opening for withdrawing the dust from said chamber, a dust separator connected with said means for receiving the dust and separating it from the air stream, means for returning the air stream from the separator to the lower portion of said chamber, a plurality of baffles in the lower portion of said chamber to direct said returned air upwardly to agitate the dust.

6. A device to collect bronzing dust comprising a chamber in which the dust is collected having an opening in the lower portion thereof, a draft creating means producing a stream of air, and having the intake thereof connected with said opening for withdrawing the dust from said chamber, a dust separator connected with said means for receiving the dust and separating it from the air stream, means for returning the air stream from the separator to the lower portion of said chamber, a plurality of baffles in the lower portion of said chamber to direct said returned air upwardly to agitate the dust, and means to regulate the force of said returned air.

7. A device to collect bronzing dust comprising a chamber in which dust is collected, suction means to withdraw the dust from said chamber, a separator connected with said suction means for receiving the dust and air withdrawn by said suction means and separating the dust from the air, means to return said air to said chamber, and a plurality of stationary baffles to direct said returned stream upwardly to agitate the air and keep the dust in suspension to assist in its removal by the suction means.

8. In a device to collect bronzing dust comprising a chamber from which dust is col-

lected having a pair of substantially aligned openings in the lower portion and at the opposite sides of said chamber, a draft creating means producing a stream of air and having
5 an intake thereof connected with one of said openings for withdrawing dust from said chamber, means to separate the dust from the stream of air and means in the lower portion of said chamber for agitating air entering
10 said other opening to assist in the removal of dust.

9. In a device to collect bronzing dust comprising, a chamber from which dust is collected having a pair of substantially aligned
15 openings in the lower portion and at the opposite sides of said chamber, a draft creating means producing a stream of air and having an intake thereof connected with one of said openings for withdrawing dust from said
20 chamber, means to separate the dust from the stream of air, a plurality of baffles in the lower portion of said chamber adjacent said openings to direct air entering said other opening upwardly to assist in maintaining the dust
25 in suspension.

In testimony whereof I have hereunto affixed my signature.

FRANK R. BELLUCHE.
